REGINALD HILTZ, OF BROOKLINE, MASSACHUSETTS

REVERSIBLE JAW COMBINATION WRENCH

Application filed April 9, 1931. Serial No. 528,928.

This invention relates to wrenches and particularly to combined monkey wrench and pipe wrench, the object being to provide an improved construction wherein the parts 5 may be readily adjusted so that the wrench may act in either case, as an ordinary monkey wrench for turning nuts and the like or as a pipe wrench for turning pipes and other round objects.

10 Another object of the invention is to provide an improved wrench wherein one of the jaws may be readily reversed so as to present a serrated edge or a straight flat edge to the opposite jaw.

15 A further object of the invention is to provide a wrench provided with a shank and stationary jaw and a sliding jaw stock with a movable and reversible jaw carried thereby, the structure being such that the jaw may 20 be reversed or moved without the use of tools.

An additional object, more specifically, is to provide a wrench wherein the worm or adjusting screw and associated parts are so formed as to function and to remain in proper 25 functioning position without the use of screws or similar means.

In the accompanying drawing—

Figure 1 is a side view of a wrench disclosing an embodiment of the invention.

30 Figure 2 is an edge view of the wrench shown in Figure 1, part of the handle being broken away.

Figure 3 is a sectional view through Figure 2 approximately on line 3—3.

35 Figure 4 is a transverse sectional view through Figure 1 on line 4—4.

Figure 5 is a transverse sectional view through Figure 1 approximately on line 5—5.

40 Fig. 6 is a detailed perspective view of a filler block disclosing certain features of the invention.

Figure 7 is a perspective view of the adjustable jaw stock casing.

45 Figure 8 is a detailed fragmentary view partly in section showing the connection between the adjustable jaw retaining pin and its supporting spring.

Referring to the accompanying drawing by numeral, 1 indicates a stationary jaw 50 merging into the shank 2 which in turn

merges into what may be termed a handle 3. The shank 2 is substantially rectangular in cross section and is provided with gear teeth 4 adapted to coat with the threads of the worm or screw 5. Straddling the shank 2 is the adjustable jaw stock casing 6 which is supplied with the filler block 7 and associated parts to make the complete reversible jaw stock 8 as shown in Figure 1. This jaw stock accommodates the reversible jaw 9 which coats with jaw 1 when the wrench is in use. Jaw 9 is provided with a straight surface 10 which is used when nuts or similar articles are being actuated but when a pipe or round object is to be actuated the jaw is turned over so that the toothed or serrated or inclined edge 11 will function as illustrated in Figure 3. The inner end of the jaw 9 is chamfered at 12 and 13 so as to allow the jaw to readily slide over the teeth 4 and also to allow the jaw to rock when used as a pipe wrench. When a pipe or other round object is gripped and power is applied to the wrench, the surface 10 will swing back and strike the surface or abutment 14 on the filler block 7. As illustrated in Figure 7, the casing 6 is provided with a number of apertures 15 which receive the respective rivets 16 which rivets extend through the respective apertures 17 of block 7 whereby the block 7 is rigidly secured to the casing 6. The casing 6 is provided with a suitable aperture 18 for accommodating the reversible jaw 19 carried by the arc-shaped spring 20. This spring is provided with a spur or elbow 21 extending into the notch 22 while the rivet 23 extends through the aperture 24 and firmly secures the end of the spring to the casing 6.

Referring again to Figure 6, it will be seen that the block 7 is provided with a substantially rectangular notch or cut-away portion 25 which merges into dovetailed notches 26 and 27, said dovetailed notches accommodating the truncated cone-shaped ends 28 and 29 of the worm or screw 5. These ends are integral with the worm 5 and are of a size to rotatably fit into the notches 26 and 27 as shown in Figure 3. This arrangement permits these end or journal members to take 100

the end or longitudinal thrust of the worm or screw 5. It will be noted that the sides or cheeks of the casing 6 act to confine these end members in notches 26 and 27 as clearly illustrated in Figure 5. It will thus be seen that there are no screws, pins or the like used in retaining the worm or screw 5 in place. This produces a simple and very strong construction as the extensions or end members 28 and 29 are integral and are of an appreciable size compared with the worm 5 so that they can take care of all the strain brought to bear thereon. In order that the thumb and finger of the operator may engage the worm 5, the casing 6 is provided with notches or cut-out portions 30 and 31 and the worm 5 is made of a size to slightly project through these notches as illustrated in Figure 2.

20 When the parts are in the position shown in Figure 1, square or flat objects may be actuated as, for instance, nuts, but should it be desired to actuate a round object, the hand of the operator will grasp the free end 25 of spring 20 and pull the free end of pin 19 out to substantially the dotted position shown in Figure 2. The jaw 9 is then grasped and moved out of the casing 6 after which it is reversed and placed back in the 30 casing as shown in Figure 3. Pin 19 is then replaced and the wrench is in proper condition to actuate a round object. It will thus be seen that without the use of tools, the wrench may be converted from an ordinary monkey wrench to a pipe wrench or the reverse. When used as an ordinary monkey wrench, the serrations or teeth 11 are adapted to fit snugly into the teeth or serrations 32 on the end of the filler block 7.

35 In this way part of the strain is taken up by the filler and part by the pin 19. Also this structure causes the adjustable jaw 9 to remain substantially rigid in respect to the adjustable jaw stock 8, thus presenting 40 a structure which will efficiently coact with a stationary jaw 11. However, when used as shown in Figure 3, jaw 9 may rock within certain limits and thereby secure substantially ideal results as a pipe wrench.

45 50 I claim:

1. A wrench comprising a stationary jaw, a shank extending from the stationary jaw, an adjustable jaw stock slidably mounted on said shank provided with serrations at one 55 end, and a reversible jaw carried by said stock at the end nearest said stationary jaw, said reversible jaw having serrations on one surface adapted to mesh with the serrations on said stock when the reversible jaw is in 60 one position.
2. In a wrench of the character described, a sliding jaw stock formed with a substantially U-shaped casing, a shank extending through said casing, said shank being provided with a stationary jaw, a filler block

rigidly connected with said casing and formed with teeth at one end and a reversible toothed jaw carried by said casing and resting against one point of said filler block when in one position and when in a second position having the teeth thereof meshing with the teeth carried by said filler block.

REGINALD HILTZ.
